(57) **CLAIM**

The ornamental design for a display screen with graphical user interface, as shown and described.

DESCRIPTION

FIG. 1 is a front view of a first embodiment of a display screen with graphical user interface showing our new design.

FIG. 2 is a front view of a second embodiment of a display screen with graphical user interface showing our new design.

FIG. 3 is a front view of a third embodiment of a display screen with graphical user interface showing our new design; and,

FIG. 4 is a front view of a fourth embodiment of a display screen with graphical user interface showing our new design.

The broken line showing of a display screen with graphical user interface is included for the purpose of showing portions of the article which form no part of the claim.

1 Claim, 4 Drawing Sheets
